US00D773484S

(12) **United States Design Patent** (10) **Patent No.:** **US D773,484 S**
(45) **Date of Patent:** **** Dec. 6, 2016**

(54) **DISPLAY SCREEN WITH GRAPHICAL USER INTERFACE**

(71) Applicant: **Tencent Technology (Shenzhen) Company Limited**, Shenzhen, Guangdong (CN)

(72) Inventors: **Ling Li**, Guangdong (CN); **Xiaobin Fang**, Guangdong (CN)

(73) Assignee: **Tencent Technology (Shenzhen) Company Limited** (CN)

(**) Term: **14 Years**

(21) Appl. No.: **29/480,357**

(22) Filed: **Jan. 24, 2014**

(51) LOC (10) Cl. **14-04**

(52) U.S. Cl.

USPC **D14/485**

(58) **Field of Classification Search**

USPC **D14/485-495**

See application file for complete search history.

(57) **CLAIM**

The ornamental design for a display screen with graphical user interface, as shown and described.

DESCRIPTION

The FIGURE is a front view of a display screen with graphical user interface showing our new design.

The broken lines showing a display screen, device, text, and portions of the graphical user interface represent environmental subject matter and form no part of the claimed design.

1 Claim, 1 Drawing Sheet
